US0D1001622S

(12) **United States Design Patent** (10) **Patent No.:** **US D1,001,622 S**
Chen (45) **Date of Patent:** **** Oct. 17, 2023**

(54) **MAGNETIC CLIP FOR FASTENING CABLES**

(71) Applicant: **Xiaojia Chen**, Shenzhen (CN)

(72) Inventor: **Xiaojia Chen**, Shenzhen (CN)

(**) Term: **15 Years**

(21) Appl. No.: **35/516,049**

(22) Filed: **Dec. 28, 2022**

(80) **Hague Agreement Data**

Int. Filing Date: **Dec. 28, 2022**

Int. Reg. No.: **DM/225995**

Int. Reg. Date: **Dec. 28, 2022**

Int. Reg. Pub. Date: **Jan. 20, 2023**

(51) **LOC (14) Cl.** **09-06**

(52) **U.S. Cl.**

USPC **D8/356**

(58) **Field of Classification Search**

USPC D8/356, 354, 349, 367

CPC B65D 63/1018; A61F 5/3792; A44B 18/00

Primary Examiner — Cynthia R Underwood

(57) **CLAIM**

The ornamental design for a magnetic clip for fastening cables, as shown and described.

DESCRIPTION

1. Magnetic clip for fastening cables

1.1 : Perspective

1.2 : Perspective

1.3 : Front

1.4 : Back

1.5 : Left

1.6 : Right

1.7 : Top

1.8 : Bottom

1.9 : Perspective
